ROSCOE W. GOOD, OF PASADENA, AND JULES CERES, OF MONTEREY PARK, CALIFORNIA,
ASSIGNORS TO THE TEXAS COMPANY, OF NEW YORK, N. Y., A CORPORATION OF
DELAWARE

ADVERTISING DISPLAY DEVICE

Application filed November 30, 1929. Serial No. 410,705.

The object of this invention is to provide a novelty in connection with an advertising display device, and is intended particularly for use in connection with advertisements relating to lubricating oils. The invention provides a mechanically operated device so constructed and operated as to be illustrative of the well known test for lubricating oils, practiced by mechanicians, in which a drop of oil 5 is placed between the thumb and fore-finger of the hand, and by the sense of touch, one gauges the "body" or lubricating value of the oil to be tested. In such a test, and with the drop of oil between the finger ends, the fingers 10 are moved slightly toward and away from each other in order to get the benefit of the sense of touch which is or may be highly developed in the finger tips. In separating the fingers, the drop of oil assumes a somewhat 15 attenuated form or outline; and it is the further object of this invention to represent, as accurately as possible, the changing outline of the oil drop as the fingers are separated.

Other objects of the invention will be apparent from the following description of the invention that is made with reference to the accompanying sheet of drawing which forms a part of this application.

Referring to the drawing,

Fig. 1 is a side elevation of a practical embodiment of our invention; and

Fig. 2 is a detail view, partly in section, showing the finger parts of the apparatus in, what may be termed, the closed position.

A figure in representation of a hand is shown at 1. This figure may be made of molded plastic material, or may be cut from suitable flat material such as lumber, composition board, or the like. In using the latter material, it is preferable that stock of such thickness be employed as will show adequate finger thickness in order to present a natural appearance, and also to afford proper support for certain elements of the structure which are associated with the finger tips and which will be hereinafter described.

In the use of this device for display purposes, it is not essential that a complete hand shall be visible in the display, since it is only 50 the fingers of the hand that are important,

and consequently only the fore part of a hand is illustrated. The thumb of the hand is shown at 2, and a fore-finger at 3. The latter, in the preferred construction, is hinged to the hand at 4, and by any convenient mechanism 55 is made to move slowly about 4 as a pivot, with a resultant up and down movement of the finger at its outer end.

To provide for movement of the finger, we show an electric motor M with a worm and 60 worm wheel drive, and an angularly disposed connecting rod between a wrist pin on the worm wheel and the hinge-pin of the fore-finger, which latter pin is fast with the finger structure, and has a bearing or bearings in 65 the hand. This specific form of drive is chosen to illustrate an operative mechanism capable of producing the slow-motion finger movements desired. It will be obvious that 70 other mechanical elements might be chosen to serve the same purpose.

Near the outer end of the fore-finger a bulbous enlargement or projection 5 is provided which is recessed to receive a socket element 6. The thumb is provided with an up-standing projection 7 the upper end of which is substantially cylindrical, and dimensioned to slide relative to and within the recess 6. The base of the projection 7 on the thumb is 75 flaring to represent, in outline, the spread of 80 an oil drop that is held between the fingers.

In operation, the motor being supplied with energy, the finger 3 will be slowly moved about the pivotal point 4, and the finger tips 85 will appear to be moved toward and away from each other, with the upper end of the projection 7 sliding telescopically within the recess 6 of the upper projection. The lower limit of movement between the fingers is illustrated in Fig. 2, where the projection 7 substantially fills the recess 6. In the limit of separating movement between the fingers, the upper end of the projection 7 remains somewhat within the recess 6 in order to avoid the 90 appearance of a break in the drop of oil under test. By proper shaping of the projections 5 and 7, and control of the finger movements 95 it is possible to closely simulate the actual appearance of a drop of oil as it is tested for 100

"body" in the common-place finger test as practiced by mechanics.

In use of this invention for display purposes, as in the window of a store or service-station, the device may be positioned behind a screen or display card, with the fingers showing through an opening in the screen or card, and an appropriate size of opening is suggested by the circle, in broken line 8, shown in Fig. 1. The purpose of this accessory, obviously, is to screen or obscure from view the operative parts of the device including the motor and its drive connections.

Having described our invention, what we claim as novel is:

1. In an advertising display device operative to simulate the known method of testing with the fingers the body of lubricating oils, comprising a figure shaped in representation of a hand with the thumb and fore-finger horizontally extended, cooperating parts secured to the thumb and finger adjacent their outer ends, and means for producing a limited relative movement of the finger and thumb toward and away from each other whereby the said cooperating parts are moved to produce the effect of finger testing a drop of oil.
2. In an advertising display device operative to simulate the known method of testing with the fingers the body of lubricating oils, comprising a figure shaped in representation of a hand with the thumb and fore-finger horizontally extended, cooperating parts secured to the thumb and finger adjacent their outer ends comprising telescoping projections, and means for producing a limited relative movement of the finger and thumb toward and away from each other whereby the said cooperating parts are moved to produce the effect of finger testing a drop of oil.
3. In an advertising display device operative to simulate the known method of testing with the fingers the body of lubricating oils, comprising a figure shaped in representation of a hand with the thumb and fore-finger horizontally extended, cooperating parts secured to the thumb and finger adjacent their outer ends comprising telescoping projections so shaped that their outline in cooperative positions resembles the outline of a drop of oil held between finger tips, and means for producing a limited relative movement of the finger and thumb toward and away from each other whereby the said cooperating parts are moved to produce the effect of finger testing a drop of oil.

In witness whereof we have hereunto set our hands this 19th day of November, 1929.

ROSCOE W. GOOD.
JULES CERES.
